(57) **CLAIM**

The ornamental design for a “drive hub assembly for a thermal transfer printer”, as shown and described.

DESCRIPTION

FIG. 1 is a front elevational view of a drive hub assembly for a thermal transfer printer showing my new design;

FIG. 2 is a left side elevational view;

FIG. 3 is a right side elevational view;

FIG. 4 is a cross section view taken along lines 4—4 in FIG. 2;

FIG. 5 is a front elevational view of the drive spindle shown separately for ease of illustration;

FIG. 6 is a left side elevational view;

FIG. 7 is a right side elevational view;

FIG. 8 is a cross section view taken along lines 8—8 in FIG. 6;

FIG. 9 is a front elevational view of the core shown separately for ease of illustration;

FIG. 10 is a left side elevational view;

FIG. 11 is a cross section view taken along lines 11—11 in FIG. 10;

FIG. 12 is a front elevational view of the drive hub shown separately for ease of illustration;

FIG. 13 is a left side elevational view;

FIG. 14 is a right side elevational view;

FIG. 15 is a cross section view taken along lines 15—15 in FIG. 13; and,

FIG. 16 is a bottom view of FIG. 14.
